CHOKER FOR TRAPPED ANIMALS

Merton E. Churchill, Arcadia, Pa.

Application August 14, 1946, Serial No. 690,514

3 Claims. (Cl. 43—85)

1

This invention relates to the trapping and execution of fur bearing animals, whereby a trapped animal may be executed by a mechanical device without damaging the pelt.

It is an object of my invention to execute a trapped animal in a minimum of time by mechanical strangulation, thereby retaining a complete unpunctured uninjured fur or pelt.

It is more particularly an object of my invention to provide two suitably curved spring actuated jaws or levers mounted with portions thereof including the actuators within a supporting casing, in combination with a releasable setting means or trigger, said mechanism being mounted on the extremity of a pole or handle.

Other objects and advantages will be revealed in the detailed description of the drawings which form a part of my specification.

In the drawings:

Figure 1 is an elevational view as seen from the front of the device, the jaws being latched in a set position ready for releasing.

Figure 2 is a longitudinal vertical sectional view showing the jaws latched in open position with the actuating springs under tension.

Figure 3 is a similar view with the jaws partly closed as they appear when engaged around the neck of a trapped animal, shown in dotted lines, the springs being in a position of intermediate tension.

Figure 4 is a sectional view taken on the line 4x—4x of Fig. 1 showing the outer ends of the jaws in section and the housing in plan.

Figure 5 is an end elevational view of the casing showing the jaw latching and trigger release in section thereon as they appear per section line 5x—5x on Fig. 4.

The drawing is illustrative of a preferred form of my invention and is not definitive thereof except so far as claimed herein.

The reference characters identify the essential parts of the invention in both the drawings and written description.

In carrying out my invention I provide an instrument particularly adapted for use in killing trapped animals, humane extinction of life being accomplished by choking the animal by clamping the neck between two curved jaws pivoted to move in intersecting paths. These jaws are spring actuated and when set in open or operative position are locked by a trigger mechanism which is released automatically when the instrument is brought into contact with the neck of an animal.

The instrument comprises a frame portion 1

2

in the form of a box-like casing and is provided with front and rear walls 2 and 3, a slotted top wall 4, a bottom 5 with upwardly curved ends 6 and 7.

The jaws 8 and 9 constituting curved levers of the first class are fulcrumed in opposed relation on a common pivot such as pin 10 carried at its ends in the walls 2 and 3 of the casing.

At one side of the top wall 4 there is a bracket 11, secured by rivets 11a parallel to the plane of movement of the jaws 8 and 9, at each end of which are a pair of outwardly projecting ears 12 and 13 carrying captive sliding latch pins 14 and 15. The latter serve to secure the jaws when they are set in open position and are disengaged by the releasing means or trigger 16. This element is formed as a bell crank lever pivoted against the edge or shoulder of the top 4 and has a broad end or plate 17 connected to the outer ends of the latch pins 14—15 which hold it in operative position on the casing. Extending outwardly from the center of the lower edge of the plate 17 is the releasing trigger comprising an offset portion 18 terminating in a lateral projection 19 adapted to be engaged with the trapped animal in the vicinity of its spine and shoulders so that when pressure is applied to it the retaining pins will be retracted to release the jaws 8 and 9.

30 The top wall 4 of the casing is provided with a longitudinal slot 20 the opposing edges of which form guides for the jaws 8 and 9 which operate in the manner of scissors or shears. Connected to the short arms or ends of the jaws within the 35 casing are tension springs 23 and 24 the opposite ends of which are articulately anchored on transversely arranged pins 25 and 26 located within the casing at each end thereof.

For conveniently handling the instrument I 40 mount it on the extremity of a pole 25 and attach it to the casing by a threaded stud 26 on the bottom 5. In order to add to the rigidity of the parts I preferably mount the stud 26 on a U-shaped bracket which spans the bottom 5 and has the ears 27 riveted to the front wall 2 and the rear wall 3 of the casing. The pole or handle 25 is of suitable length. For example if a silver fox is caught in a trap having an anchor chain the fox would have a considerable range of movement

45 substantially twice the length of the chain. Hence the handle should be long enough so that the operator of the mechanical executor may keep beyond the reach of any vicious trapped animal.

50 When it is desired to set the device it is merely

necessary to force the curved jaws 8 and 9 apart far enough so that the captive pins 14 and 15 may engage over the inner edges of the jaws to retain them in open position against the tension of their respective springs 23 and 24. When in this set position the trigger 19 is in the full line position of Fig. 5. The operator upon approaching the trapped animal holds the device in a suitable depending position to bring the jaws over the back of the neck of the animal so that the lateral projection or trigger engages either the base of the skull or the end of the spine just back of its neck. This relatively light pressure releases the jaws which encircle the neck of the animal resulting in strangling it in a minimum of time. The tension of the springs operating the jaws is such that they are propelled together to stop both the circulation of blood and the passage of air through the trachea.

I have found in my trapping work that an animal may be thus executed in a matter of seconds, usually less than one-half a minute. Because of this complete and rapid strangulation there is very little time for the animal to struggle. The result accomplished is the preservation of a complete unpunctured and undamaged pelt.

What I claim and desire to protect by Letters Patent is:

1. A choking mechanism for trapped animals, comprising a supporting frame, levers fulcrumed thereon, each having a long arm and a short arm, the former extending in parallelism beyond the frame and being curved toward each other, springs each attached to the frame at one end and to said short arms and serving to force said long

arms toward each other, and a setting and releasing means located on the frame.

2. A choker for trapped animals as set forth in claim 1, in which the setting and releasing means is mounted in a bracket secured to the frame in a position parallel to said long arms, said frame having guides at its ends, latch pins slidably mounted in said guides having free ends movable into and out of the path of said long arms, and a bell-crank lever articulatedly connected with said pins and fulcrumed against the side of said frame, said lever having an offset arm adapted to engage the body of the trapped animal and serving to release said jaws for engagement about the neck of the trapped animal.

3. A choker for trapped animals, as set forth in claim 1, the sub-structure comprising a setting means for retaining the levers in operative position comprising a bracket having guides at its ends carrying latch pins having heads, a trigger articulated on the frame having a portion serving to retract the pins, and an arm extending away from said frame and adapted to engage the body of the trapped animal.
